US00D594963S

(12) **United States Design Patent**
McElveen et al.

(10) **Patent No.:** US D594,963 S
(45) **Date of Patent:** ** Jun. 23, 2009

(54) **SHROUD FOR COOLING TOWER FAN MOTOR**

(75) Inventors: **Robert McElveen**, Anderson, SC (US);
William E. Martin, Greenville, SC (US)

(73) Assignee: **Reliance Electric Technologies, LLC**,
Greenville, SC (US)

(**) Term: **14 Years**

(21) Appl. No.: **29/329,494**

(22) Filed: **Dec. 16, 2008**

(51) **LOC (9) Cl.** 23-04

(52) **U.S. Cl.** D23/386

(58) **Field of Classification Search** D23/386-393,

(57) **CLAIM**

The ornamental design for a shroud for cooling tower fan motor, as shown and described.

DESCRIPTION

FIG. 1 is a perspective view of a shroud for cooling tower fan motor showing our new design;

FIG. 2 is a representative side view of the shroud of FIG. 1;

FIG. 3 is a bottom view of the shroud of FIG. 1; and,

FIG. 4 is a top view of the shroud of FIG. 1.
